UNITED STATES PATENT OFFICE

159,159

COMBINED WORK CONTROL PANEL AND SERVICE DESK

Anthony Mohr, Chicago, Ill., assignor to Crystal
Manufacturing Co., Inc., Chicago, Ill., a corporation of Illinois

Application November 15, 1949, Serial No. 6,050

Term of patent 7 years

(Cl. D26—5)

To all whom it may concern:

Be it known that I, Anthony Mohr, a citizen of the United States, residing at Chicago, in the county of Cook and State of Illinois, have invented a new, original, and ornamental Design for a Combined Work Control Panel and Service Desk, of which the following is a specification, reference being had to the accompanying drawings, forming part thereof.

Fig. 1 is a front elevational view of a combined work control panel and service desk embodying my new design.

Fig. 2 is a side elevational view thereof taken from the right of Fig. 1 and showing the drawer of the desk partly withdrawn.

The opposite side of the design is the same as the side shown and the back is plain.

I claim:

The ornamental design for a combined work control panel and service desk, substantially as shown and described.

ANTHONY MOHR.
